HAT BOX

Ruth M. Van Doren, 440 S. Kenilworth, Elmhurst, Ill.
Filed Apr. 8, 1959, Ser. No. 804,903
4 Claims. (Cl. 206—8)

This invention relates to a hat box for storing a plurality of hats in readily accessible condition, and it is an object of the invention to provide an improved hat box of that character for the storage of women's hats and the like.

Previously known hat boxes have had various objectionable characteristics such as a lack of easy accessibility to the hats stored therein, failure to provide protection to the hats to prevent them from being dented and from becoming entangled with each other, insufficient capacity, and excessive size relative to the number of hats that can properly be received therein. In contrast to previously known hat boxes, a hat box constructed in accordance with the present invention provides proper storage for a plurality of hats, protects the hats against crushing, prevents entanglement of the hats, and provides quick visibility and easy accessibility to each hat stored therein without disturbing the others. At the same time, the invention provides for storage and protection of a substantial number of hats within an enclosure of reasonable dimensions.

Accordingly, it is an object of the present invention to provide an improved hat box incorporating means for supporting a plurality of hats therein in readily accessible positions. Another object of the invention is to provide an improved hat box having a readily openable and closable door and rotatable hat supporting means within the box by means of which any one of a plurality of hats carried by the rotatable support means may quickly and selectively be brought adjacent the open door for observation or removal.

It is a still further object of the present invention to provide an improved hat box including rotatable hat supporting means in which the individual hat supporting means are adjustably positioned to permit reception of hats of various shapes. Another object of the invention is to provide an improved hat box incorporating hat supporting means for a plurality of hats, the hat supporting means being so constructed and arranged that a brim portion of each hat supported thereon may nest within the crown of an adjacent hat, thereby causing the hats to occupy a minimum of space.

It is still another object of the invention to provide an improved hat box having means by which any one of the hats within the box may be moved to a position for convenient removal without any of the other hats in the box being touched by the hands.

Further features of the invention pertain to the arrangement of the elements of the hat box, whereby the above outlined and additional features thereof are attained.

The invention, both as to its organization and method of operation, together with further objects and advantages thereof, will best be understood by reference to the following description of one embodiment of the invention, taken in connection with the accompanying drawing, wherein:

FIGURE 1 is a perspective view of a hat box incorporating the present invention;

FIG. 2 is a left side elevational view of the same hat box with the near side wall thereof removed and with the interior apparatus shown partially in cross-section;

FIG. 3 is a plan view of the same hat box with the top cover broken away; and,

FIG. 4 is an enlarged elevational view of a central hub member, viewed in the direction of the arrows on the line

2

4—4 of FIG. 3, portions of the hub member being shown in cross-section.

In the embodiment of the invention illustrated in the drawing, the hat box includes a bottom wall 11, three upstanding fixed side walls 12, 13 and 14, a door 15, and a top wall 16 which preferably may also be opened if desired. The door 15 includes a window 17 through which the interior of the box may be observed when the hat box is closed. A clasp 18 of any suitable type secures an upper flange 15a of the door 15 to the top wall 16 so as to maintain the hat box tightly closed. The top wall 16 is preferably provided with downturned edge flanges 16a which overlay the side walls 12 and 14 to prevent the entrance of dust into the box.

15 The enclosure described above may be formed of any suitable material and, if desired, may be fabricated of a good grade of heavy cardboard covered with fabric or heavy paper, as suggested in the drawing. In this case, no special provision need be made for hinging the door 20 15 and the top cover 16, the outer covering of cloth or heavy paper and the cardboard, properly creased, permitting the desired hinge action of the top cover along the rear edge 16a thereof and the proper hinge action of the door along the lower edge 15a thereof. The window 25 17 may consist of a clear plastic film cemented across the opening of the door 15 in the interest of economy but may comprise a pane of glass. In either case, the glass or plastic may be secured directly to the frame of the door 15. Other satisfactory materials for construction 30 of the enclosure will be apparent to those skilled in the art.

Where a relatively light material is employed in the construction of the enclosure, the bottom wall 11 thereof is preferably reinforced by a plate 21 of wood or 35 heavy fiberboard, this plate being secured to the bottom wall 11 by adhesive or by suitable fasteners such as rivets. An upstanding post 22 is secured to the plate 21 at the center of the box by adhesive or by suitable fasteners such as nails or screws, and a rotatable hub 23 is supported upon the top of the post 22 and is maintained in alignment therewith by an axially arranged pin 24 which is set into the post 22 and the hub 23, as shown in FIGS. 2 and 4. The pin 24 may be loosely received within the post 22 or the hub 23, or both, so as 45 to permit easy rotation of the hub 23 about the axis of the pin and about the axis of the post.

As seen best in FIG. 4, the hub 23 is provided with a plurality of pairs of transverse openings 25 extending through the hub 23 in one direction. Similar pairs of 50 openings 26 extend through the hub 23 at right angles to the openings 25. These openings 25 and 26 permit adjustable mounting of hat supporting elements on the hub 23, as will presently be described.

Four radially arranged hat supporting elements 30 are 55 provided in the presently illustrated embodiment of the invention. Each element includes a pad 31 of soft material such as sponge rubber, which is of such shape as to enter a crown of a hat and provide soft, non-slipping support for a hat. It will be understood that the pads 31 need 60 not fit the hat which it supports but may fit loosely therein in the manner suggested in FIG. 3, wherein four hats are illustrated in phantom lines. Each hat supporting element 30 also includes a pad supporting frame 32 of heavy wire. This wire supporting frame is preferably 65 bent in the form illustrated in FIG. 2, and the pad 31 is slit, as at 31a, to permit reception of the supporting frame. More specifically, each frame includes a U-shaped portion 33 embedded or received within the slit 31a, and a pair of arms 34 (see FIGS. 2 and 3). The arms 34 are 70 so spaced as to permit convenient reception of the free ends thereof into a pair of openings 25 or 26 in the

hub 23. The pad 31, and in particular that portion of the pad arranged radially inwardly of the slit 31a, may be wider than the spacing between the arms 34 such that it is compressed therebetween, as clearly seen in FIG. 2. The arrangement of the U-shaped portion 33 of the wire frame 32 within the slit 31a, and the compression of the radially inner portion of the pad between the arms 34, firmly anchors the pad to the wire frame. It will be understood that in assembling a wire frame and a pad, one arm 34 of the wire frame is thrust through the slit 31a in the pad, after which the wire frame is twisted with respect to the pad to draw the U-shaped portion 33 of the wire frame into the slit 31a, it being further understood, however, that other forms of pads 31 may be employed and that the particular manner in which the pads are mounted upon the radiating arms of the supports 32 may vary accordingly. In any event, however, the U-shaped portion 33 of each wire frame is suitably bent or each pad 31 is so shaped that the pad itself is disposed angularly with respect to the radially directed arms 34, as best seen in FIG. 3.

The two arms 34 of a wire frame 32 may be inserted into a pair of openings 25 or 26 at any desired height, and the arms 34 of another wire frame may then be inserted into a pair of openings 25 or 26 at any level except that occupied by the arms of the wire frame of any previously installed hat supporting element 30. Accordingly, where four hat supporting elements are arranged in one hat box, it is necessary in the present embodiment that they be at four slightly differing levels. However, the openings 25 and 26 are preferably closely spaced vertically of each other such that there is little difference in the level of the four hat supporting elements. As an alternate construction, however, it will readily be appreciated by those skilled in the art that the arms 34 need not extend so deeply into the openings 25 and 26 so that the arms of the supports may be disposed at two levels or, if desired, all at the same level.

Four hats may be arranged on the four hat supporting elements 30 in the manner suggested in FIG. 3. By virtue of the fact that the hub 23 and the hat supporting elements mounted thereon are rotatable about a vertical axis, any of the four hats arranged within the box may be brought to a position adjacent the door 15, such that any selected hat becomes readily accessible through the door 15 without the necessity of opening the top wall 16. The enclosure or volume of the hat box is permitted to be of substantially reduced dimensions or value by virtue of the fact that the hat supporting pads 31 are oriented angularly with respect to the radial arms 34 so that a brim portion of each hat may nest within the crown of a hat supported on an adjacent hat supporting element, in the manner illustrated in FIG. 3. More specifically, the hat supporting elements are so oriented with respect to the hub member 23 that the planes of the brims of hats supported thereby deviate substantially, and all in the same sense, from perpendicularity to lines extending radially from the axis of the hub member and intersecting the centers of the hats.

It will be observed that the present hat box provides storage for a plurality of hats, protects the hats against crushing, prevents entanglement of the hats, and provides quick visibility and accessibility of each hat stored therein. At the same time, it provides for storage and protection of a substantial number of hats within an enclosure of reasonable dimensions. Furthermore, the hat supporting elements 30 are adjustable vertically with respect to the box and radially with respect to the hub 23. The wire frames may also be bent to alter the vertical tilting, or to alter or adjust the nesting effect of the hats supported thereby. The hat box is thereby adjustable to hats of various, mixed sizes and shapes.

In rotating the hub 23 upon the upper end of post 22 in order to bring the hats successively into position in

front of the door 15, the user of the hat box may reach inside the door and propel the hub simply by pushing laterally on the successive hats supported upon the pads 31. The touching of the hats in order to cause rotation may be undesirable in some instances, however, particularly when the hats are of a delicate construction or when touching of the hats might cause them to become dirty or otherwise blemished. In order to permit rotation of the hub 23 without touching the hats within the box, a pair of generally half-circular shaped wire frames 40 are embodied in the structure in the manner shown in the drawings. The opposite ends of each of these frames 40 are inserted into the opposite ends of the respective lowermost openings 26 in the hub 23, the ends of the frame being wedged or otherwise suitably fixed within these openings. From the opposite ends of each opening 26, each wire frame 40 extends downwardly generally alongside the upstanding post 22 but clear thereof to a level adjacent to but above the platform 21, and then 20 radially outwardly and thence circumferentially, as best seen in FIG. 3, so that the two rings 40 together provided, in effect, a complete circular ring. The forward portion of the effective circular ring provided by the two frames 40 is disposed closely adjacent the door 15 so that when the door is opened the ring may conveniently be grasped in the hand and turned, thereby causing the hub 23 to rotate to carry the hats successively to a position in front of the door opening. The frames 40 thus provide a very simple and extremely inexpensive means for permitting rotation of the hub 23 and the hat supporting means without causing the hats within the box to be touched.

While there has been described what is at present considered to be the preferred embodiment of the invention, it will be understood that various modifications may be made therein, and it is intended to cover in the appended claims all such modifications as fall within the true spirit and scope of the invention.

I claim:

1. A hat box for storing a plurality of hats each including a hollow crown and a brim extending outwardly therefrom and substantially normal to the axis of the crown, comprising an enclosure having a readily openable and closable door permitting ready access to the interior thereof, a hub member rotatably mounted within said enclosure for rotation about a vertical axis, a plurality of arms mounted on said hub member and extending outwardly laterally therefrom and spaced apart radially from each other, and a hat supporting pad mounted on the end of each of said arms and being adapted to fit within the crown of an associated hat and firmly to support the hat thereon with the axis of the crown disposed along the radial support axis of said pad, said radial support axis of said pad being disposed at an angle with respect to the radial axis of the attached arm so that the brim of the hat supported thereby is directed into the crown of an adjacent hat on an adjacent pad.

2. A hat box for storing a plurality of hats each including a hollow crown and a brim extending outwardly therefrom and substantially normal to the axis of the crown, comprising a box having a readily openable and closable door in a side wall thereof permitting ready access to the interior of the box, a hub member rotatably mounted within said enclosure for rotation about a vertical axis, a plurality of arms mounted on said hub member and extending outwardly laterally therefrom and spaced apart radially from each other, and a hat supporting pad mounted on the end of each of said arms and being adapted to fit within the crown of an associated hat and firmly to support the hat thereon with the axis of the crown disposed along the radial support axis of said pad, said radial support axis of said pad being disposed at an angle with respect to the radial axis of the attached arm so that the brim of the hat supported thereby is di-

rected into the crown of an adjacent hat on an adjacent pad, said hub member being rotatable so as to carry the hats on said pads to a position in front of said door to permit convenient and selective removal of the hats from said box.

3. A hat box for storing a plurality of hats, each including a hollow crown and a brim extending outwardly therefrom and substantially normal to the axis of the crown, comprising a box having a readily openable and closable door in a side wall thereof permitting ready access to the interior of the box, a hub member rotatably mounted within said enclosure for rotation about a vertical axis, four arms mounted on said hub member and extending outwardly laterally therefrom and spaced apart radially 90° from each other, and a hat supporting pad mounted on the end of each of said arms and being adapted to fit within the crown of an associated hat and firmly to support the hat thereon with the axis of the crown disposed along the radial support axis of said pad, said radial support axis of said pad being disposed at an angle with respect to the radial axis of the attached arm so that the brim of the hat supported thereby is directed into the crown of an adjacent hat on an adjacent pad, said hub member being rotatable so as to carry the hats on said pads to a position in front of said door to permit convenient and selective removal of the hats from said box.

4. A hat box for storing a plurality of hats each including a hollow crown and a brim extending outwardly therefrom and substantially normal to the axis of the

crown, comprising an enclosure having a readily openable and closable door permitting ready access to the interior thereof, a hub member rotatably mounted within said enclosure for rotation about a vertical axis, said hub member having a plurality of openings therein arranged vertically therealong and angularly spaced therearound, a plurality of arms each including a prong disposed in one of said openings to mount said arms on said hub member with said arms extending outwardly laterally therefrom and spaced apart radially from each other, said arms being adjustable both vertically and radially about said hub member, and a hat supporting pad mounted on the end of each of said arms and being adapted to fit within the crown of an associated hat and firmly to support the hat thereon with the axis of the crown disposed along the radial support axis of said pad, said radial support axis of said pad being disposed at an angle with respect to the radial axis of the attached arm so that the brim of the hat supported thereby is directed into the crown of an adjacent hat on an adjacent pad.
